UNITED STATES PATENT OFFICE.

JACOB P. WRIGHT, OF BARBERTON, OHIO, ASSIGNOR TO THE DIAMOND MATCH COMPANY, OF CHICAGO, ILLINOIS, A CORPORATION OF ILLINOIS.

MECHANISM FOR STRAIGHTENING AND ASSEMBLING SPLINTS.

Application filed October 21, 1924. Serial No. 744,864.

To all whom it may concern:

Be it known that I, JACOB P. WRIGHT, a citizen of the United States, and resident of Barberton, in the county of Summit and

5 State of Ohio, have invented certain new and useful Improvements in Mechanism for Straightening and Assembling Splints, of which the following is a specification.

This invention relates to mechanism for straightening and assembling match splints; and its object is the provision of simple and efficient means whereby quantities of splints are rapidly separated from a promiscuously mixed mass and arranged in an orderly manner. The invention has been especially, though not exclusively, designed for use in connection with or as an attachment to the type of match making machines wherein splints contained in a magazine are ejected 20 row by row therefrom and inserted endwise into an adjacent endless carrier by means of which the splints are transported through the match making cycle; my invention when thus co-operatively associated with a match 25 making machine insuring the constant filling of the magazine with properly arranged splints.

The invention, generally stated, comprises a rotary receptacle into which the splints, in mass, are delivered from a suitable source 30 of splint supply, said receptacle including parallel rows of open pockets or compartments by means of which groups of splints are separated from the mass and arranged in parallelism during the rotation of the receptacle, and means constructed and arranged to intercept and uniformly support the succeeding groups of splints which escape 35 from the said pockets or compartments when the latter progress to the bottom of the receptacle.

More specifically, the invention comprises a rotary splint receiving cage having therein a cellular structure which provides parallel rows of pockets or compartments opening radially from the interior to the exterior of the cage, a guard partially encircling the cage and presenting at the bottom 45 of the latter an opening through which the contents of the pockets or compartments are discharged, and a continuously driven conveyor which receives the discharged splints in succeeding rows and transfers them in an orderly manner to a suitable receiver.

The invention also comprises novel features of construction and combinations of parts, all of which will be hereinafter described and claimed.

In the drawings—

Figure 1 is a front elevation of splint straightening and assembling mechanism embodying the principle of my invention, showing its co-operative arrangement and connection with a match making machine.

Fig. 2 is an end elevation of the said mechanism and connections.

Fig. 3 is a transverse vertical section through a rotary cage element of the mechanism, its guard, and the underlying portion of a splint arranging and conveying belt.

Fig. 4 is a longitudinal vertical section through the cage construction, as on the line 4—4 of Fig. 3.

Fig. 5 is a detached perspective view of the guard casing for the cage, showing an adjacent air pipe for clearing splints from the ascending pockets of the cage.

Fig. 6 is a similar view, with parts partly broken away, of a cellular frame structure as removed from the rotary cage, which structure affords a series of open splint receiving pockets for the cage.

Fig. 7 is a perspective view of one of the transverse partitions of the cellular frame structure.

Fig. 8 is a similar view, partly in section, of one of the end heads of the rotary cage.

Fig. 9 is a fragmentary section of adjacent portions of the cellular frame structure and its guard casing.

Referring to the drawings, 10 designates a rotary cage comprising two circular end heads 11 and a cylindrical, cellular structure between the same, said structure providing parallel rows of pockets or compartments opening radially from the interior to the exterior of the cage. In the present instance this structure comprises succeeding spaced-bars 12, which are secured at their ends, as at 13, to and around the peripheries of the respective heads, and transverse partitions 14 which are interposed at intervals apart between adjacent bars; the partitions being conveniently affixed to the bars by means of end tongues 15 thereon entered in suitable apertures 15' in the bars. The partitions and bars of each row are so spaced

and arranged that the width of each compartment is less and the length of the compartment is slightly greater than the length of a splint, so that quantities of the splints contained within the rotating cage enter the lowermost pockets in a horizontal longitudinal position substantially parallel with the side walls 14 of the pockets. Each of the end heads 11 is provided with a central opening 16 through which freely extends into the cage the neck 17 of a conduit 18 leading from a source of splint supply and being of such capacity as to discharge the splints in large quantities into the cage.

Partially encircling the cage is a casing 19, the lower portion of which presents a longitudinal opening 20 below the path of the pockets, which casing thus serves as an efficient guard to prevent the escape of the splints from the cage until the pockets successively reach the opening. In the present instance the casing is suspended by suitably located hangers 21.

The cage may be continuously rotated by any suitable mechanism. In the present instance the end heads 11 are provided with suitable rims or tires 22 that rest upon pairs of flanged wheels 23 located adjacent the respective ends of the cage. These wheels are carried by parallel shafts 24 having their bearings 25 on a suitable supporting frame, as 26, one of said shafts being equipped with a pulley 27 that is connected by means of a belt 28 with a pulley 29 on the shaft of a suitably-disposed electric motor 30. Hence continuous motion is transmitted from the motor to the cage, and the latter may be rotated at any predetermined speed by varying the speed of the motor in the usual manner.

During the rotation of the cage the splints therein are constantly rolling as in a tumbling barrel, which operation has the effect of smoothing the splints by attrition. At the same time quantities of the splints are separated from the mass and arranged in the progressing pockets in parallel position, and hence as such pockets approach and reach their lowermost position their contents escape the guard member, and in consequence the groups of splints drop from the succeeding rows of open pockets and below the cage.

Arranged directly beneath and adjacent the rotating cage is the upper horizontal run of a broad endless belt conveyer 31 which travels in a path at right angles to the axis of rotation of the cage and intercepts the succeeding rows of parallel splints as they escape from the pockets of the cage. The conveyer 31 underlies the width of the cage and extends thence a substantial distance to the point of discharge. This conveyer is supported and guided by pulleys 32, the shafts 33 of which have their bearings 34

on the main supporting frame. One of the shafts 33 bears a pulley 35 which is driven by means of a belt 36 from a pulley 37 on a driven element, as, for example, the shaft 38 of an adjacent match making machine. The speed of the conveyer 31 is constant, and it is so timed in relation to that of the rotating cage that the conveyer assists the passage of the splints from the respective rectangular pockets of the cage and positions them in parallelism on the conveyer and with the splints of succeeding rows in substantial alinement longitudinally. The splints thus orderly arranged on the conveyer are transferred thereby to a suitable receptacle or receptacles.

As a simple and efficient means to prevent the continued upward travel of splints that may be contained within the pockets of the rotating cage, and also to contribute to the agitation of the mass, I provide the guard casing 19, with a longitudinal slot 39 at the ascending side of the cage, and I arrange adjacent to and longitudinally of such slot an air pipe 40 having lateral vents 41 opening into the slot. This pipe is connected with a suitable source of supply of compressed air, and hence the air, flowing under pressure through the slot of the casing into the cage, forces from the succeeding rows of up-going pockets when they are passing the slot, any splints that may be contained in the pockets and also contributes to the agitation of the splints within the cage. In the present instance the rows of splints, in train, are delivered by the conveyer 31 to an elongated feed trough 42 through which travels a partitioned blade-conveyer 43, said trough being so constructed and arranged that the splints are delivered in substantial parallelism into and transversely of the trough. This trough has a rapid jarring action imparted thereto in order to insure the compact settling of the splints within the trough. The trough and its appurtenances herein illustrated are old and they therefore need no particular description herein. Suffice it to say, that the endless blade conveyer 43 is arranged to travel longitudinally of and through the trough, and by means of its spaced blades 44 partition the trough into progressing compartments into which the splints are uniformly deposited as rapidly as they are discharged from the belt conveyer 31. The trough 42 is provided at its discharging end with an extension 45 into which the parallelized splints are delivered by the blade conveyer 43, such extension having at its extremity a depending discharge nozzle 46 through which the splints are delivered into the splint magazine of any known or approved type of match-making machine equipped with setting mechanism for ejecting the lowermost splints from the maga-

zine and inserting them row by row into the perforations of an endless carrier, as 47.

By varying the speed of the rotary cage, through the motor control, the delivery of 5 the succeeding rows of splints from the cage to the transfer conveyer 31 can be regulated to meet the requirements of the match machine; it being noted that by increasing or reducing the speed of the cage the number 10 of splints delivered thereby to the conveyer will be proportionately changed.

It is to be understood that I do not limit my invention to the specific construction 15 herein disclosed as the mechanism may be modified within the principle of my invention and the scope of the appended claims.

I claim:-

1. In mechanism for straightening and assembling splints, the combination of a rotary 20 receptacle including parallel rows of rectangular compartments, each compartment being proportioned to receive and carry a group of splints in parallelism, a continuously moving conveyer mounted to travel 25 directly below and in angular relation to the axis of rotation of the receptacle, and means permitting the discharge of the contents of each succeeding row of compartments upon the progressing conveyer during 30 the rotation of the receptacle.

2. In mechanism for straightening and assembling splints, the combination of a rotary receptacle including parallel rows of rectangular compartments, each compartment being proportioned to receive and carry a group of splints in parallelism, a continuously moving conveyer mounted to travel directly below and in angular relation to the axis of rotation of the receptacle, and means permitting the discharge of the contents of each succeeding row of compartments upon the progressing conveyer during 35 the rotation of the receptacle, and variable speed means for actuating the receptacle.

3. In mechanism for straightening and assembling splints, the combination of a rotary receptacle having parallel rows of peripheral compartments opening from the interior to the exterior of the receptacle, each 50 compartment being of less width and of greater length than the length of a splint and being designed to receive and carry a group of splints in parallelism, a guard casing partially encircling said receptacle and presenting an outlet longitudinally of and below the receptacle, and means beneath said outlet for receiving the contents 55 of the progressing compartments.

4. In mechanism for straightening and assembling splints, the combination of a rotary receptacle having parallel rows of peripheral compartments opening from the interior to the exterior of the receptacle, each 60 compartment being of less width and of greater length than the length of a splint

and being designed to receive and carry a group of splints in parallelism, a guard casing partially encircling said receptacle and presenting an outlet longitudinally of and below the receptacle, and a continuously 70 moving conveyer mounted beneath said outlet and arranged to intercept the succeeding rows of groups of splints discharged from the progressing compartments.

5. In mechanism for straightening and assembling splints, the combination of a rotary cage-like receptacle comprising a cylindrical structure providing parallel rows of compartments opening from the interior to the exterior of the receptacle, each compartment being of less width and of greater 75 length than the length of a splint and being designed to receive and carry a group of splints in parallelism, a guard casing partially encircling said structure and presenting an outlet longitudinally of and below the structure, and a continuously moving conveyer mounted beneath said outlet and arranged to intercept the succeeding rows 80 of groups of splints discharged from the compartments.

6. In mechanism for straightening and assembling splints, the combination of a rotary receptacle including a cylindrical cellular structure composed of bars in spaced-parallel relation to each other and spaced-apart partitions between adjacent bars, whereby parallel rows of rectangular compartments opening from the interior to the exterior of the structure are provided, each compartment being of less width and of greater length than the length of a splint and being designed to receive and carry a group of splints in parallelism, a guard casing partially encircling said structure and presenting an outlet longitudinally of and below the structure, and a continuously moving conveyer mounted beneath said outlet and arranged to intercept the succeeding rows 90 of groups of splints discharged from the compartments.

7. In mechanism for straightening and assembling splints, the combination with a rotary receptacle having parallel rows of peripheral compartments opening from the interior to the exterior of the receptacle, each compartment being of less width and of greater length than the length of a splint and being designed to receive and carry a group of splints in parallelism, of a guard 100 casing partially encircling said receptacle and presenting an outlet longitudinally of and below the receptacle, and pneumatic

split agitating means operative to force the splints from the up-going compartments 105 during their rotary travel.

8. In mechanism for straightening and assembling splints, the combination with a rotary receptacle having parallel rows of peripheral compartments opening from the 110

interior to the exterior of the receptacle, each compartment being of less width and of greater length than a splint and being designed to receive and carry a group of splints in parallelism, of a guard casing partially encircling said receptacle and presenting an outlet longitudinally of and below the receptacle, said casing having an

opening therein adjacent the ascending side of the receptacle, and an air-pipe located ¹⁰ adjacent said opening and having vents directed to the opening.

Signed at Barberton in the county of Summit and State of Ohio this 18 day of October A. D. 1924.

JACOB P. WRIGHT.
